UNITED STATES PATENT OFFICE.

ROBERT W. BROOKS, OF PARKER'S GROVE, KENTUCKY.

POST-HOLE DIGGER.

SPECIFICATION forming part of Letters Patent No. 680,483, dated August 8, 1899.

Application filed April 14, 1898. Serial No. 677,534. (No model.)

To all whom it may concern:

Be it known that I, ROBERT W. BROOKS, a citizen of the United States, residing at Parker's Grove, in the county of Larue and State 5 of Kentucky, have invented a certain new and useful Improvement in Post-Hole Diggers, of which the following is a specification.

My invention relates to a new and useful improvement in post-hole diggers, and has for 10 its object to provide an exceedingly simple and effective device of this description by the use of which a hole approximately the shape and size of the butt of the post may be formed and the dirt removed therefrom; and a further object of my invention is to so form such 15 a device as to avoid the disturbing of the ground to an unnecessary degree, so that when the post is placed within the hole but little filling and tamping are needed.

With these ends in view this invention consists in the details of construction and combination of elements, as hereinafter set forth and then specifically designated by the claim.

In order that those skilled in the art to which 25 this invention appertains may understand how to make and use the same, the construction and operation will now be described in detail, referring to the accompanying drawings, forming a part of this specification, in 30 which—

Figure 1 is a perspective of a digger made in accordance with my improvement, showing the ejector in its lowered position; and Fig. 2, a vertical section thereof, showing the body 35 of the digger forced within the ground.

In carrying out my invention as here embodied, A represents the body of the digger, which is here shown rectangular in shape, being approximately for ordinary work six by 40 eight inches, and consists of a suitable piece of metal bent or otherwise formed to this shape, having its top and bottom open, while one end thereof is also left open, as indicated at B, the object of which is to afford means for observing the dirt being removed from the hole. Shank-strips C are riveted or otherwise secured to the body of the digger and converge 45 upward and are attached to the handle D, which is preferably of tubular shape, having 50 its upper end flattened, as indicated at E, after the manner of a crowbar. An ejector F is fitted within the body of the digger, so as to move up and down therein, while a square rod G is secured to this ejector and passes up-

ward within the handle and through a square 55 hole in the lower end thereof, so as to assist in the guidance of the ejector. This rod also passes through the brace H, which extends across the top of the body, said brace also serving as a stop for limiting the upward and 60 downward movement of the ejector, the latter movement being limited by the foot-piece I, which is attached to the rod G.

The operation of my improvement in practice is as follows: The location of the hole to 65 be dug being selected, the digger is forced into the ground by a sudden blow or pressure after the manner of a spade, which process will force the ejector upward, and when the proper depth is reached the digger is lifted from the 70 hole, drawing with it the dirt inclosed therein, and this dirt is ejected from the digger by simply placing the foot upon the piece I and forcing the ejector downward.

One of the principal advantages of my improvement is that a rectangular hole may be dug of any desired size without removing or disturbing an unnecessary amount of the dirt, as in the case of a round digger, since approximately the shape of the butt-end of the 80 post is formed in the ground and of approximately the size for the reception of said post, so that when the post is set but little filling in is needed, which renders the post more firm than would otherwise be the case. 85

The flattened end E of the digger may be used for the loosening or removal of stones and the like.

Having thus fully described my invention, what I claim as new and useful is— 90

In combination with a body of the character described, a hollow handle having at the lower end inturned flanges, a rod slidable in the handle and guided by the flanges, a brace extending from side to side of the body and 95 having an aperture in which the rod is slidable, the said brace coöperating with the flanges of the handle in guiding the rod, an ejector on the rod, a foot-piece having a clamp adjustable on the rod, substantially as described. 100

In testimony whereof I have hereunto affixed my signature in the presence of two subscribing witnesses.

ROBERT W. BROOKS.
